(57) **CLAIM**

The ornamental design for a wireless doorbell set, as shown and described.

DESCRIPTION

FIG. 1 is a front perspective view of a receiver part of my design for a wireless doorbell set;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of a transmitter part of my design for a wireless doorbell set;

FIG. 10 is a rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof; and,

FIG. 17 is an elevation view of the wireless doorbell set, shown in a configuration of use, showing the receiver and the transmitter arranged on opposing sides of the outer wall of a structure.

The broken lines shown in FIG. 17 illustrate Environmental structure.

The broken lines form no part of the claimed design.
